George R. Joughins INVENTOR

UNITED STATES PATENT OFFICE.

GEORGE ROBERT JOUGHINS, OF NEW YORK, N. Y.

PNEUMATIC SPRING.

Application filed January 15, 1923. Serial No. 612 844.

My invention relates to pneumatic springs and is embodied in a controlled recoil air cushion device, particularly adapted for use as a spring under vehicles but which may be used in any position that is suitable and wherever a steel or fluid or other class of spring is now provided for absorbing shocks, especially if it is desired to control the recoil.

10 It will be understood that the drawings herewith showing the device are entirely diagrammatic and are not made to scale.

Figure 1 is a vertical section of the cylinder on a plane through its center line, the 15 piston and some other parts are, however, not in section. The closed end may be designated as the top.

Fig. 2 is a plan view of the valve, 6, used on the diaphragms and Fig. 3 a side elevation of the same. Fig. 4 is an end view of the valve in the plunger and Fig. 5 a cross section of the same. Figure 6 is a bottom section at A—A of the rod 5.

The main parts of the spring comprise a 25 cylinder 1 closed at one end by a cover 2; a piston or plunger 3 fitted to the other end.

Several floating diaphragms 4, unattached to the cylinder or the piston, fit into the cylinder from wall to wall and divide the cylinder into completely enclosed spaces and are supported in their concentric position by a rod or rods, such as the extension rod 5 attached to the cover of the closed end, and 30 are distance spaced as shown in the accompanying drawing, and comparatively air tight, by being made of a suitable diameter both at the circumference and in the hole so that each diaphragm, wherever pre- 35 arranged to form a division of the cylinder, will rest both on the inclined edges of the cylinder and on the extension rod. All these diaphragms are fitted with several ample sized check valves 6; illustrated by Figures 40 2 and 3, showing a portion of the dia- phragms, 4, with the superimposed valves, 6, suitably attached thereto in an ordinary manner and preferably having a spring 6' 45 to normally hold the valve in the closed po- sition, opening upwards only, to allow the air which may be quickly displaced by the inward action of the plunger to flow freely 50 towards the closed end, they also have con- stricted perforations 7 which compel the highly compressed air to return slowly to-

wards the plunger and thus modify and control the recoil.

Ordinary metal springs, 13, of suitable design may be arranged between the several diaphragms, and the cylinder cover, for the purpose of holding them symmetrical and to keep them down to their respective positions if the rush of air tends to lift them up too high.

To operate the spring it must be charged with sufficient compressed air through an ordinary inlet supply valve, 14 to move the plunger to a normal loaded position; its action when working may be described as follows. In its normal loaded position the plunger may displace one or two or three of the diaphragms from off their seats and carry them some distance towards the closed end of the cylinder; any heavy shock now applied to the plunger will cause it to travel still further towards the upper end and it will carry along some more diaphragms; in the meantime the compressed air opens up the check valves, perhaps unseats the diaphragms a little, and is nearly all forced by the plunger into the upper part of the cylinder where it is trapped and confined by the upper diaphragms. If now the load on the plunger is partially relieved, it will tend to return to its normal position, but can only do so at a rate governed by the amount of the highly compressed air which can filter through the perforations provided in the diaphragms. Each diaphragm becomes seated as the plunger recedes and immediately commences to do its part in controlling the recoil which may, by controlling the return flow of the air, be modified to a large extent, as may be desired.

The extension rod shown at 5 has one end fixed in the head which seals the end of the cylinder, it is tapered for a distance to support the diaphragms and then made parallel to fit into the plunger which thus supports the other end of the rod. A leakage groove 95 is indicated at 8 and illustrated by Figure 6, which shows an end view of the rod, 5, and the leakage groove, 8.

In the drawing, the inside walls of the cylinder are shown as enlarged towards the 105 upper end but this taper is made for the better support of the diaphragms at their circumference.

The leakage from the plunger is inter- 110 cepted by a flexible hose connection 9 made

of rubber or other material which would be cemented and banded to the lower end of the cylinder and to the bottom of the plunger. If it is made of a corrugated section to have a concertina action it will act as a pump and return the leakage to the cylinder through a conduit with check valves, as shown at 10 which is further illustrated by Figures 4 and 5, showing the plunger, 3, the valve, 10, the valve guide, 11, and the cotter, 12, to limit the movement of the valve.

Sets of such springs may be arranged in nests, each spring may have its diaphragms spaced differently to produce a more uniform recoil.

What I claim is:

1. A pneumatic spring, in which a gaseous fluid enclosed and controlled within a rigid metal cylinder is the only load supporting resilient element, comprising a cylinder closed at one end; disc shaped diaphragms within the cylinder and placed transversely thereof to divide the cylinder space into separate portions and which have a longitudinal movement relative thereto; a reciprocating plunger fitted to the other end of the cylinder and means for transmitting the gaseous fluid and controlling its movements to and from the various portions into which the cylinder is divided by the diaphragms, the cylinder cover and the plunger.

2. The combination of a gaseous fluid enclosed and controlled within a rigid metal cylinder and forming the only load supporting resilient element, a cylinder, closed at one end; a reciprocating plunger at the other end; distance spaced unattached diaphragms within the cylinder and transverse thereof and means for conveying and controlling

compressed gaseous fluid into and out of said spaces.

3. A pneumatic spring comprising a cylinder having its inside bore tapered and enlarged towards its upper end; a cover to seal said end; transverse movable diaphragms seated at spaced distances within said tapered portion and a parallel portion at the other end of the cylinder within which a reciprocating plunger is applied.

4. A pneumatic spring consisting of a cylinder; a cylinder cover at one end to which is fixed an extension rod protruding inside the cylinder, said extension rod being tapered and enlarged towards its lower end and transverse movable diaphragms seated thereon at spaced distances.

5. A pneumatic spring comprising a tapered bored cylinder closed at one end; a parallel reciprocating plunger at the other end and movable diaphragms placed within the cylinder and transverse thereof, said diaphragms resting upon the tapered side walls of said cylinder and upon a tapered extension rod attached to the cylinder cover of the closed end.

6. In a pneumatic spring, a leakage pump comprising a flexible hose having one end attached to the barrel of the cylinder, outside, and the other end to the bottom of the plunger; a conduit for the return of the leakage leading from the space within the hose to that within the lower part of the cylinder and having a check valve fitted thereto.

Signed at New York city, in the county of New York and State of New York, this sixth day of January, A. D. 1923.

GEORGE ROBERT JOUGHINS.
